UNITED STATES PATENT OFFICE.

HENRY E. BULLOCK, OF CHICAGO, ILLINOIS, ASSIGNOR TO BULLOCK TRACTOR CO., OF CHICAGO, ILLINOIS, A CORPORATION OF ILLINOIS.

TRACTION-WHEEL.

1,124,287.

Specification of Letters Patent. Patented Jan. 12, 1915.

Application filed September 26, 1914. Serial No. 863,779.

To all whom it may concern:

Be it known that I, HENRY E. BULLOCK, of Chicago, in the county of Cook and State of Illinois, have invented certain new and useful Improvements in Traction-Wheels; and I do hereby declare that the following description of my said invention, taken in connection with the accompanying sheet of drawings, forms a full, clear, and exact specification, which will enable others skilled in the art to which my said invention appertains or with which it is closely connected to make and use the same.

This invention has general reference to traction wheels, and while adapted for use in all kinds of cast car, and similar wheels, it is especially applicable to bearing wheels, such as are employed in traction engines of self-laying track type, that run upon said endless tracks and that support the upper or slack-runs of such endless tracks.

Its object is to enhance the durability of such traction wheels and to render repairs thereof comparatively inexpensive.

To attain this object my invention consists in the production of a wheel of such hardness that ordinary machining thereon is difficult and practically impossible, and to provide the same with a removable core or bushing of a softer metal capable of being readily machined. An example of such a wheel is shown in the accompanying drawings, which serve to illustrate my invention more fully, and in which—

Figure 1 is a longitudinal sectional elevation, and Fig. 2 is a sectional elevation on line 2—2 of Fig. 1 of the same. Fig. 3 is likewise a longitudinal sectional elevation of my improved wheel illustrating means for holding the central bushing in position, and Fig. 4 is an end-elevation of the same.

Like parts are designated by the same characters and symbols of reference in all the figures.

A in these drawings designates a car, or other wheel, having the usual tread 16, and flange 17. This wheel, as usually made in cast iron has a central bore 18, for the reception of an axle, which bore is machined in order to fit said axle either by a driving, or a rotating fit. Such a wheel cannot be successfully produced in casting except in a metal, capable of being machine-bored to receive said axle, and therefore, the life of

such a wheel is limited; and to increase its durability the tread and inner flank of the flange, are usually "chilled". This method of procedure, however, is not sufficient in case of a wheel, such as a bearing wheel in tractors of the endless track type where the tread of the wheel rolls, nearly continuously, on a sandy or gritty track and is soon worn to such an extent as to make its further use impossible. To overcome this objection I cast the body of the wheel in white-iron; being the metal used in the production of malleable iron, which, owing to its extreme hardness, is especially capable of resisting wear and cannot be machined; and in this casting I provide centrally a bore larger than that required for the axle and secure in this bore a bushing of metal capable of being readily machined. This latter bushing 19, may be of soft gray iron, brass, bronze, or other suitable metal capable of being bored and faced, and it may be permanently secured in the wheel by placing a previously prepared bushing into the mold and then casting the wheel in hard iron around said bushing, after which the bushing may be finally bored to receive the axle. This wheel possesses a life many times that of a chilled, or a soft-tread wheel, and is as cheap, if not cheaper than these wheels.

My method of producing these wheels is especially well adapted to the production of twin-wheels, so called, being a pair of traction wheels in spaced relation, united, integrally, by a hub, 20, as shown in Figs. 1 and 3. In order to produce this class of wheels when designed to rotate on the axle, (in contradistinction to the usual car-wheels in which the wheels are fixed to the axle and the latter rotated in bearings) in which case the wear of the bearing in the wheel would soon render the wheel defective and useless, I provide the same with a removable bushing 19, and fasten this bushing in the wheel in such a manner that the bushing may be removed and replaced when worn, thereby producing quite a saving in cost of repairing these wheels. To accomplish this result I core the wheel larger than the external diameter of the bushing 19, and hold this bushing in position by a series of bolts 21, as shown at the right of Fig. 3, or by other similar means. I prefer, however, to

2
hold this bushing in place by pouring a soft metal composition that will melt at a comparatively low heat, such as Babbitt metal and the like, in the space between the bushing and the core-opening in the wheel, a method which is extremely inexpensive, since, when it is desired to renew a bushing, the wheel may be heated to melt the lining, to withdraw the worn bushing, the soft metal being suitable for re-use and hence no expense connected with its employment.

It will now be observed that by my present method of producing these wheels, I do not need to bore the wheel proper, nor machine the outside of the bushing, the only machining necessary being the chucking of the wheel after the bushing has been secured in the hub, and then boring the bush-

ing as at 22, to insure concentricity with the tread.

Having thus fully described this invention, I claim as new and desire to secure by Letters Patent of the United States:

A wheel of the type described having a body entirely composed of white iron, a central core of a metal capable of being machined, and holding means for said core. 25

In testimony that I claim the foregoing as my invention I have hereunto set my hand in the presence of two subscribing 30 witnesses.

HENRY E. BULLOCK.

Witnesses:

J. M. HEDLUND,
MICHAEL J. STARK.
